AWARE.

OIL-BURNER SAFETY DEVICE.

Application filed January 30, 1926. Serial No. 84,843.

This invention relates to fuel burners, and in particular it relates to that type of fuel burners which operate on liquid fuel such as oil. The invention has also to do with an 5 improved safety means for controlling the burner to eliminate dangerous operating conditions and to prevent the existence of fire hazards.

This invention will be hereinafter de- 10 scribed in detail as being incorporated in an oil burner which is particularly adapted for heating homes, apartments, office buildings and the like. The particular burner herein referred to is substantially automatic in its 15 operations. While the improved safety means has an especial advantage when incorporated in the automatic oil burners for heating the homes it is to be understood that it may be incorporated in automatic burners 20 employed for other purposes, and that it may also be incorporated in semi-automatic oil burners which at more or less regular intervals require the attention of an attendant. Also, it may be noted that the improved 25 safety means herein disclosed may be incorporated in a non-automatic oil burner. Also, the safety device may form an integral part of a burner, or it may be provided as an accessory which may readily be attached to oil 30 burners already manufactured.

In respect to oil burners particularly employed for heating the homes or dwellings, it is the common practice to have such burners controlled by or be responsive to a thermostatic means or element located at some desirable place in the home such as in the hall. In some instances, however, it may be desirable to have the thermostatic element located near the furnace or boiler. In any event the ther- 35 mostatic control element is so located that it will operate to properly control the desired heating of the home or apartment, or other buildings where such a burner is installed. The usual operation of burners so installed 40 is intermittent, for as the dwelling becomes sufficiently warm the thermostatic element operates to close down the burner, and in the event the home becomes chilled the thermostatic element operates to start the burner. 45 Thus it will be seen that usually the oil burners for home purposes are intermittent in their operations.

In other burners employed for home use, the burner may be of that type which is continuous in its operation and is so constructed 55 as to operate with a high or low flame, depending upon the heat required. In the event of the failure of burning of this continuously operating burner there would be a flooding of the oil in the burner and usually 60 an overflow onto the floor of the basement thus creating an exceptionally dangerous fire hazard. The improved safety means herein- 65 after disclosed in detail operates to prevent the existence of such conditions. Likewise, 70 in the burners which are intermittent in their operation the invention hereinafter described operates to prevent the existence of fire hazards due to overflowing of oil when the burner fails to ignite at any one of the 75 periods when it normally is required to begin operations in response to the action of the thermostatic element. Also this safety device becomes operable to stop the burner when the burning stops for any reason and 80 thereby prevents the existence of the fire hazard. This invention presents a further improvement in that the oil fuel in either case is not permitted to become exposed to the atmosphere, thus the flooding of the burner it- 85 self and the flooding of the basement floor is eliminated.

It is recognized that in some burners which have heretofore been manufactured there has been incorporated therein certain devices or 90 safety means which operate to close down the burners when abnormal conditions exist. One of these safety means is the collection of oil which has been fed to the burner but which was not ignited. This collected oil heretofore has been conveyed to a container 95 and when a certain amount or quantity thereof has been collected the container moves, usually due to weight of the oil, and operates in some manner to stop the operations of the burner. These containers which collect the oil have become known as "drip buckets". One of the great disadvantages of such type of 100 safety means is that the oil collected becomes exposed to the atmosphere and thereby presents an exceptionally dangerous fire hazard. Another disadvantage is that when the burner has been closed down by reason of the collection of a material quantity of oil in the

drip bucket that it becomes necessary to remove the bucket from its position which keeps the burner from operating and to thereafter pour the oil into some container or to carry the oil to the main supply tank which may be located in the yard. It has been the experience with burners which include this type of drip bucket safety control that there is always some oil spilled around on the floor of the basement and around the burner itself. It will be noted that this collected oil is always open to the atmosphere, thus the existence of danger, especially when, as is usually the case, the drip bucket is positioned in close association with the burner itself which becomes heated during its normal operation. Therefore the fire hazard becomes particularly dangerous.

The main object of this invention is, therefore, to provide an improved and novel safety means which eliminates the disadvantages hereinbefore enumerated.

A further object of the invention is to provide an improved portion of the control for liquid fuel burners in which the fuel in its natural state, i. e., as oil in its liquid state, is employed for closing down the burner when combustion is not initiated or when combustion ceases.

Another and particular object of this invention is to provide such an improved safety control means for an oil burner that the oil in its natural or liquid state may be employed to operate a safety control and to maintain this "acting" oil so that it is never free to the atmosphere.

A further object of the invention is to provide in an oil burner a novel closed oil system for operating a safety means for controlling the burner.

Another object of the invention is to provide an improved safety control for an oil burner to prevent the existence of a dangerous fire hazard by providing an enclosed oil system in which a certain amount of the oil collected will operate the safety means to close down the burner, and the operating oil thereafter will be returned to the oil supply or to the oil supply system. This improvement also includes the maintaining of this collected oil so that it never becomes free to the atmosphere.

A still further object of this invention is to provide an improved and novel safety means which is responsive to oil collected from the burner and which is designed to compensate for the small quantity of oil which is collected during the normal starting of the burner so that the safety means will not then become active, but will become active when abnormal quantities of oil are collected.

Other objects and advantages of this invention will be noted upon reading the detailed description hereinafter set forth.

It will be understood that when the terms

"acting" oil or "collected" oil are used, they will apply in their broad sense and are directed to the oil in its normal or liquid state which has been collected after it has been passed into the burner or combustion chamber.

The preferred form of this invention and its incorporation in an oil burner is illustrated in the accompanying drawings where-

in:

Fig. 1 is an elevational view of the exterior of a preferred oil burner showing the safety means incorporated therein;

Fig. 2 is a sectional view in part of a portion of the oil burner disclosing one form of burner construction for collecting oil which has been passed into the burner;

Fig. 3 is a sectional view taken on the lines 3-3 of Fig. 2;

Fig. 4 is a sectional view of a modified burner construction for collecting oil which has been passed into the burner;

Fig. 5 is a sectional view taken on the line 5-5 of Fig. 4;

Fig. 6 is a sectional view in part of a portion of the safety means disclosing an electric switch and a suitable operating mechanism therefor;

Fig. 7 is a sectional view of one part of the safety means construction showing another view of the electric switch and an oil reservoir with various valves;

Fig. 8 is a sectional view of a modified construction of safety operating means;

Fig. 9 is a sectional view of a valve associated with the mechanism diagrammatically illustrated in Fig. 11 and also shows a suitable push button for short circuiting the switch;

Fig. 10 is a diagrammatic view of the preferred oil conduit system with the safety means therein;

Fig. 11 is a diagrammatic view of the modified form of oil conduit system with the safety means therein; and

Fig. 12 is a top plan view of an indicator which shows the position of the electric switch.

Referring now to these illustrations, a side view of the preferred form of oil burner is shown in Fig. 1. This burner consists of a rear portion 1 which includes the operating parts and a front portion or tube 2 within which there is a partial burning of the fuel before it is discharged from the extreme end 3 of the burner. The construction of the tube portion of the burner may be more readily appreciated by reference to Fig. 2 which is a sectional view of the tube showing a suitable atomizing nozzle 4 in dotted lines for spraying the fuel into the tube 2. The atomized mixture issuing from the nozzle may be ignited by any suitable means, preferably by means of a spark-plug. Additional air is added to the mixture and the air plus the

burning mixture move through the tube 2 and issue from the end 3 thereof into the lower part of the furnace or boiler being heated.

While the preferred form of burner herein illustrated includes the tube 2, it will be understood that the successful operation of the safety means hereinafter to be described may be obtained with burners which have the nozzle 4 thereof introduce the mixture directly into the lower part of the furnace or boiler.

In the burner as herein shown, it is preferred to control the same by means of a room thermostat connected in a control circuit such as an electrical control circuit. The control circuit is not here shown but such circuits are commonly employed in many of the present home oil burners.

With the form of burner herein described it is preferred to provide a pump 5 for drawing the fuel from a suitable supply tank as shown in Figs. 10 and 11. This pump 5 continuously provides an oil bowl 6 with a sufficient quantity of oil so that the oil may be drawn to the nozzle 4 by means of the air passing through the nozzle 4 under pressure. It will be understood that burners which employ the gravity feed of oil directly to the nozzle 4 may be also employed.

The safety means herein disclosed as being one of the main features of this invention consists in general of means for collecting unburned oil which has been issued from the nozzle 4 and to employ that collected oil for purposes of controlling the operation of the burner in cases of the existence of abnormal conditions therein. It is a further feature of this invention to maintain this collected oil within a closed conduit system to thereby eliminate fire hazards which would be present if this collected oil was open to the atmosphere. It is also an additional feature that this collected oil may be returned to the supply of fuel for the burner or to the intake side of the pump 5.

The improved safety device becomes operable when initiation of ignition fails upon the starting of the burner or whenever the combustion or burning of the oil ceases for any one of several possible reasons.

Any suitable form of apparatus may be employed for taking advantage of the presence of this unburned oil which is collected within the tube 2 in order to vary the control of the burner to preferably stop the burner. In providing one form of suitable means for taking advantage of this collected oil, it has been found desirable to form within the tube of the burner an annular bead 7 to assist in collecting oil which has not been burned and a suitable form of apparatus such as pipe 8 is provided for conducting this collected oil into reservoir 9. See Figs. 1, 2, 6 and 7. Referring to Fig. 2 the end of the pipe 8 is provided with a suitable protecting means such as a cover 10 for preventing foreign materials

from being blown into the pipe and for equalizing the gas pressures within the tube so that the oil will readily flow from the pipe 8 through an opening 11 in the cover 10 to the reservoir 9 through a conduit 12.

A suitable modified form of construction of the tube 2 for accomplishing the same purpose of collecting and conducting the unburned oil is illustrated in Figs. 4 and 5. In this modification there is provided a trough 14 so that the oil collected will readily flow to the cover 10 and from there through opening 11 and through a suitable strainer 15 to the inlet pipe 12 for the reservoir 9.

The closed conduit system herein provided for conducting the collected oil from the burner to the supply preferably consists of the pipe 8, the reservoir 9, an outlet pipe 16 to fuel supply pipe 17 which leads to a suitable fuel supply and which also has the branch 18 leading to the pump 5. It is to be understood that this pipe 18 leads to the suction side of the suction pump 5 as it is preferred to move the oil from the main fuel supply to the pump 5 by means of suction. It will be seen that with this preferred type of safety means that the closed oil conduit system never permits the collected oil to become exposed to the atmosphere. When this safety means is employed with oil burners which have the nozzle 4 introduced in the furnace or boiler to be heated it will be understood that any suitable means such as a trough or a pan may be employed within the furnace to collect such oil that is unburned and to return the same to the reservoir 9 by any suitable form of piping means. The pipe 8 herein illustrated provides a satisfactory means for conducting the oil which is unburned in the tube 2 to the reservoir 9 and from there to the fuel supply or to the suction pump 5.

It has been found from experience in the operation of oil burners that upon starting there will be a certain amount of oil which issues from the nozzle 4 and which is not burned for the reason that ignition of the mixture does not always take place instantaneously with the issue of the atomized fuel from the nozzle 4. When combustion is initiated within the tube 2 then the oil which issues from nozzle 4 becomes ignited and there will be no further substantial quantity of unburned oil collected. The oil which is unburned during the normal starting and initiation of combustion in the burner will pass through pipe 8 to the reservoir 9 and this quantity of unburned oil will be herein-after referred to as a normal quantity which normally accumulated during any start of the burner. It is desirable to return this quantity of oil to the fuel supply so that there will not be an accumulation of these normal quantities of oil within the reservoir 9. Any desired apparatus may be provided for with-

drawing this normal amount of oil from the reservoir 9 after each starting so that the reservoir will not become filled. In the present construction there is provided a valve 19 in the base of the reservoir 9 through which this oil may pass to the pipe 16 and from there to the fuel supply tank 20 (see Fig. 10) or back to the suction side of the pump 5 as shown in Figs. 1 and 10. This normal accumulation of oil in reservoir 9 operates to raise a suitable float 21 mounted therein, and the float will be raised from the collar 22 mounted on stem 24 thereby permitting the weights 25 to raise the stem so that valve 19 is opened and the effect of the suction from pump 5 will withdraw oil from the reservoir 9 and allow the float 21 to again set itself on collar 22 thereby returning the stem 24 to close valve 19.

As heretofore indicated, one of the features of the invention is to employ the oil collected from the tube 2 for purposes of controlling the operation of the burner. In the disclosures herein this collected oil is employed to operate the float 21. Also a modified form of using this collected oil is shown in Fig. 8, wherein the weight of the collected oil is employed to modify the control circuit of the burner instead of simply employing the quantity of collected oil in accordance with the construction illustrated in Figs. 6 and 7. It is to be understood, however, that in the broad scope either of these forms may be employed or that any other construction of apparatus responsive to the oil collected from tube 2 may be employed for modifying or changing the control of the oil burner.

In the event the initiation of combustion in the tube 2 has not been successful then there will be an abnormal accumulation of oil in the tube 2 and this oil will flow to the reservoir 9 and raises the oil level therein. The size of the opening of valve 19 is such that the flow of oil therethrough will be less than the flow of the oil into the reservoir 9 from the pipe 8. This is the preferred construction although modifications may be made thereof. Normally the float 21 in reservoir 9 assumes the position at level H_1 during the normal running of the burner. The level H_2 shown in Fig. 7 illustrates the usual position to which the float 21 may be raised due to the accumulation of the normal amount of oil collected during successful initiation of combustion within the tube 2. When there is an abnormal accumulation of oil within the reservoir 9 the float 21 is raised to level H_3 and the float has then engaged the weights 25 and has raised them so that they force the stem 24 downward to close the valve 19 and thereby prevent further flow of oil through that valve into the return pipe 16.

As one of the features of this invention is the provision of a complete safety means for

controlling the operation of the burner, it is desired to have a suitable form of means co-operating with and responsive to the movement of float 21 due to the collection of an abnormal amount of oil in reservoir 9. The device for controlling the burner which cooperates with the movement of the float 21 is herein preferably shown as a switch 26 which is connected in the electrical control circuit for the burner and which when responding to the movement of the float 21 preferably operates to change the control circuit so that the burner operations are stopped. In providing a suitable type of mechanical connection between the float 21 and the switch 26 there are here provided stems 27, see Fig. 6, which are engaged by the float 21 when it rises to its position H_3 . These stems are suitably mounted on a cross beam 28 which in turn is attached to a plate 29 carried by a suitable spindle which is held in a support 30. The upward movement of the stems 27 and the plate 29 carries projection 31 of the plate 29 into contact with a suitable pin 32 mounted on the switch 26 and the further rise of the float 21 causes projection 31 to move pin 32 thereby tipping switch 26 to open the same thus varying the control for the burner and preferably causing the burner to stop. In the preferred construction herein the stopping of the burner will stop the operation of the suction pump 5 which supplies fuel from tank 20 to the burner. Thus when there is an abnormal accumulation of collected oil in reservoir 9 there is a cessation of feed of oil to the burner.

The switch 26 and its mechanism are mounted within a suitable housing 34 in order that they may be properly protected and there is herein shown a desired form of indicator 35 over which a pointer 36 is moved by arm 37 carried by the switch 26. This indicator will show whether the switch 26 is off or on. Thus by a glance at the indicator it is readily noted when the reservoir 9 is full of collected oil.

After the burner has been shut down due to the accumulation of collected oil which represents the failure of initiation of combustion within the burner or the cessation of combustion due to any other cause, it becomes desirable to reposition or reset this safety means so that the burner may be again started. In repositioning this safety means it becomes desirable to return switch 26 to its normal position so that an electric circuit is completed therethrough. Any suitable means may be employed for this purpose. It is, however, found desirable to provide some manual operating means and there is, therefore, illustrated a suitable valve 38 provided with a handle 39. It may be stated that this valve may be remotely controlled if desired. When the valve 38 is turned the collected oil

within reservoir 9 may pass to a second reservoir 40 until the level of the oil in reservoir 9 has returned from level H_3 to level H_1 . The valve 38 may then be returned to its normal closed position. In returning the float 21 to its position H_1 the switch 26 will automatically be returned to its closed position as illustrated in Fig. 6 and the normal control of the burner then becomes effective and the burner may then be restarted.

The oil collected in the second reservoir 40 may be returned to the fuel supply tank 20 by any suitable means which does not expose the oil to the atmosphere and for this purpose there is provided a suitable ball valve 41 which controls a passage way 42 (see Fig. 7) which connects with the pipe 16 and from there to tank 20 or to the suction pump 5. In reference to Fig. 10 the ball valve 41' is shown as being connected to the supply pipe 17. Either of these particular connections may be employed. Both are shown for purposes of illustration but in the preferred construction it is desirable to have passage way 42 connect directly to the conduit 16.

It will be seen from this construction that when the burner is started the suction developed in pipe 16 will draw the oil which has been drained into the second reservoir 40 back to the suction side of the pump 5. The ball valve 41 will also act to prevent any oil which may be in pipe 18 from entering the second reservoir 40 when the burner has been stopped for any reason should the oil in pipe 18 not return directly to the supply tank 20. It will be noted that this second reservoir 40 will practically always be more or less empty as it is within the influence of the suction developed within pipe 16.

A modified form of construction which permits the return of the abnormal amount of oil in reservoir 9 to the suction pump or to the fuel supply 20 is illustrated diagrammatically in Fig. 11 and a portion of that construction is illustrated in detail in Fig. 9. This modified construction eliminates the use of the second reservoir 40 and ball valve 41'. Referring now to Fig. 11 there is provided a conduit 44 having therein a valve 45 which is normally held in a closed position by reason of spring 46 and which is manually opened by the movement of a suitable handle 47. The conduit 44 is directly connected to the reservoir 9 as illustrated and to the pipe 18 leading to the suction pump 5. With this modified construction the reservoir 9 is drained by lifting the handle 47 to open the valve 45 and to cause lever 48 to engage an electrical push button 49 that closes two electrical conductors 50 and 51 which act to short circuit the switch 26. When this button 49 has been pressed the control circuit for the burner will be completed and the pump 5 started thereby creating suction

within conduit 44 to draw the oil from reservoir 9 thus permitting float 21 to lower to level H_1 and allow the switch 26 to return to its normal closed position. When the oil has been drained from reservoir 9 the handle 47 may be lowered and the valve 45 closed and the safety device is then reset to its normal operating condition and the burner will continue its normal operations.

From the foregoing description it will be seen that the liquid fuel which has been collected in tube 2 will be returned to the fuel supply tank or to the suction side of the pump, as the case may be, without becoming exposed to the atmosphere. Thus a dangerous fire hazard which has heretofore existed is entirely eliminated. This feature becomes very important from that point of view and from the point of view from providing a self-operative, efficient and satisfactory oil fuel burner which requires only a relatively small amount of attention. It will also be noted that the unburned oil which is collected from tube 2 is employed to operate a safety means when an abnormal quantity of the oil collects. It will further be noted that the normal or small amount of oil which is collected during a successful starting of the burner is compensated for by returning that amount of oil to the fuel supply so that there is no danger of having the safety device operated after the burner has been started a few times by having an accumulation of the normal quantities of oil in reservoir 9. In this connection it may be stated that the safety device automatically operates to compensate itself when the normal amount of collected fuel flows into reservoir 9.

The modified form of the safety device as illustrated in Fig. 8 shows the preferred construction of apparatus employed to control the operation of the burner by the weight of the oil which collects. In place of the reservoir 9 there is provided a housing 52 within which there is provided a container 54 mounted on pivots 55 so that it may be readily tipped by reason of the weight of the oil caught therein. An adjustable counter balance 56 is provided for adjusting the operation of the device so that it may be responsive to different weights of oil employed or to quantities thereof which collect.

Within the housing 52 there is provided a stationary tube 57 to which the pipe 16 is connected so that a suction will be provided to withdraw the oil from the container 54. On the exterior of the lower end of tube 57 and slidably thereon is a suitable frame 58 which carries valve pin 59 and which is provided with openings 60 to permit the oil in the container 54 to flow to the interior of frame 58 so that it may pass through the valve to conduit 16. The frame 58 is suitably mounted in a yoke piece 61 pivoted on exten-

sion 62 of the tube 57. This yoke 61 is provided with an extension 63 which is adapted to oscillate between the adjustable set screws 64 and 65 supported on a portion of the container 54 as illustrated.

The oil collected in the tube 2 will flow through the pipe 8 and into the pipe 12 which leads into housing 52 and permits the collected oil to drop into container 54. The normal position of the apparatus is illustrated in Fig. 8 with the valve pin 59 closed by reason of extension 66 of frame 58 resting on a suitable abutment 67 forming part of the container 54.

As the collected oil fills the container 54 the weight of this oil will overbalance the weight 56 and cause the container to tip about its pivoted point 55. The frame 58 will drop until extension 63 pivoted at point 68 is engaged by adjustable set screw 64. This will sufficiently open valve pin 59 to permit the normal amount of oil received through pipe 12 to be carried through tube 57 and pipe 16 back to the suction side of the pump 5. Thus this construction which operates due to the weight of the collected oil compensates for the normal amount of oil collected from the tube 2 during a successful starting of the burner.

When there is an abnormal collection of oil in container 54 it will overbalance the weight 56 to such an extent that the container will be materially tipped causing the set screw 64 to carry the extension 63 downward and thus cause the frame 58 to be raised so that valve pin 59 will again seat and prevent the oil from being drawn through tube 57 and into the pipe 16 by reason of the suction.

By reason of this material tipping of container 54 and the downward movement of set screw 64, this set screw will also engage an arm 69 of a suitable rocker arm 70 which is connected by a link 71 and extension 72 to the electric switch 26 which is electrically connected to the control circuit of the burner. The oscillation of the rocker arm 70, it will be noted, tips the switch 26 so that it will open and thereby open the control circuit of the burner and cause the burner to cease its operations. The stopping of the burner also stops the supply of fuel to the burner. Thus, an abnormal accumulation of oil collected from the tube 2 acts to control the operation of the burner and the parts of the apparatus are so constructed and assembled that they cooperate upon this abnormal accumulation of oil to stop the burner.

When the burner has automatically been stopped by reason of this abnormal quantity of oil in the safety device it is again desirable to perform a manual operation to reset or recondition the burner for normal operation. In this preferred construction there is provided a push button 74 mounted in a suitable frame 75 which is supported on the housing

52. By pushing this button 74 the switch 26 is again closed and the burner starts operation. Also the movement of button 74 moves the rocker arm 70 so that set screw 64 is raised and extension 63 then becomes free and permits the frame 58 to drop thereby opening the valve to tube 57 and permitting the suction created by the suction pump 5 to remove the accumulated oil within the container 54 to permit the balance weight to return the container 54 and the other operating parts thereof to their normal operating positions.

From the foregoing description of the preferred form of apparatus and the modifications thereof it will be seen that the efficiency of the oil burner is materially increased. It will also be seen that the unburned oil which collects is returned to the fuel supply without permitting the collected oil to become exposed to the atmosphere thus eliminating a very dangerous fire hazard and eliminating one of the present material disadvantages of oil burners. It will further be seen that the collected oil in passing from the burner back to the supply will be employed to modify the control means of the burner so that there may be a change in the operation of the burner. In this particular instance the change is the causing of the burner to stop, or, primarily to cause the stopping of the feeding of fuel to the burner.

It will be understood that while we have here described in detail a particular embodiment of our invention for purposes of full disclosures, and some detailed features which we are specifically claiming for a special advantage, many changes and modifications may be made in the particular construction and arrangement of parts without departing from the broad scope of our invention which is outlined in the subjoined claims.

We claim:

1. In an oil burner the combination of a combustion chamber, means for feeding fuel thereto, fuel ignition means, a safety means consisting of a closed oil conduit system connecting said combustion chamber and a fuel supply for said burner, and means mounted in said conduit system and adapted to cooperate with the fuel feeding means to stop the flow of fuel to said combustion chamber when a predetermined quantity of fuel has passed into said conduit system, said fuel stopping means also acting to permit a small amount of fuel normally collected during the initiation of combustion to return to the fuel supply for the burner without operating the safety means to stop the flow of fuel to the burner.

2. In an oil burner, a safety device adapted to stop the feed of fuel to said burner when initiation of combustion fails, said device including means for collecting unburned fuel and automatic means responsive to a normal amount of oil collected during successful initi-

- ation of combustion for returning this normal amount to the fuel supply for said burner.
3. In an oil burner, a safety device adapted to stop the feed of fuel to said burner when initiation of combustion fails, said device comprising means for collecting unburned fuel, automatic means responsive to a normal amount of oil collected during initiation of combustion for returning this normal amount to the fuel supply for said burner, and additional means associated with said automatic means and being responsive to the collection of an abnormal quantity of fuel for stopping the flow of fuel to the burner.
- 15 4. In an oil burner, a safety device adapted to stop the feed of fuel to said burner upon failure to obtain ignition, said device including means for collecting the fuel, automatic means responsive to a normal amount of oil collected during successful initiation of combustion for returning this normal amount to the fuel supply for said burner, and a closed oil conduit system connected to the combustion chamber of said burner and to a fuel supply therefor for conducting the oil from said combustion chamber back to the fuel supply.
- 20 5. In an oil burner, the combination of a combustion chamber, fuel feeding means, fuel ignition means, a closed conduit system connecting said combustion chamber with a fuel supply for said burner, and a valve in said conduit system for controlling the movement of fuel collected from said combustion chamber to said supply, said valve adapted to be operated automatically to open under normal operations of said burner to permit the normal amount of oil collected while obtaining combustion to be automatically returned to the fuel supply of said burner.
- 25 6. In an oil burner the combination of a combustion chamber, means for feeding fuel to said chamber, fuel ignition means, a safety means consisting of a closed oil conduit system connected to said combustion chamber and to a fuel supply for said burner, a valve incorporated in said conduit system for governing the flow of fuel collected from said combustion chamber to said fuel supply, means for automatically opening said valve to allow the normal amount of fuel collected during initiation of combustion to flow to said fuel supply, said valve control means acting to close said valve when an abnormal amount of fuel has been collected from said combustion chamber.
- 30 7. In an oil burner the combination of a combustion chamber, means for feeding fuel to said chamber, fuel ignition means, a safety means consisting of a closed oil conduit system connected to said combustion chamber and to a fuel supply for said burner, a valve incorporated in said conduit system for governing the flow of fuel collected during initiation of combustion to said fuel supply, control means for said valve, said valve con-
- trol means acting to close said valve when an abnormal amount of fuel has passed into said oil system from said combustion chamber, and means associated with said valve control means for stopping the flow of fuel to said combustion chamber when an abnormal amount of fuel has passed into said system.
- 35 8. In an oil burner the combination of a combustion chamber, means for feeding fuel to said chamber, fuel ignition means, a safety means consisting of a closed oil conduit system connected to said combustion chamber and to a fuel supply for said burner, a valve incorporated in said conduit system for governing the flow of fuel collected from said combustion chamber to said fuel supply, said valve being of such size as to permit a lesser flow of oil therethrough than the capacity of said conduit system for collecting the fuel from said combustion chamber, and means responsive to the amount of oil collected for governing the operation of said valve to be automatically opened when a small amount of collected oil flows into said conduit system and to be closed when an abnormal amount of oil flows into said system.
- 40 9. In an oil burner the combination of a combustion chamber, a fuel supply therefor, a pump for conducting fuel from said supply to said combustion chamber, fuel ignition means, a closed fuel conduit system connected between said combustion chamber and said pump, and safety means incorporated in said fuel conduit system for stopping the supply of fuel to said combustion chamber when abnormal quantities of fuel pass into said conduit system.
- 45 10. In an oil burner the combination of a combustion chamber, a fuel supply therefor, a suction pump for controlling the movement of fuel from said supply to said combustion chamber, a closed fuel conduit system connecting said combustion chamber to the suction side of said pump, said conduit system adapted to receive unburned fuel from said combustion chamber and to return the same to said suction pump, and a valve in said conduit system for governing the flow of fuel collected from said combustion chamber to said pump.
- 50 11. In an oil burner the combination of a combustion chamber, a fuel supply therefor, a suction pump for controlling the movement of fuel from said supply to said combustion chamber, a closed fuel conduit system connecting said combustion chamber to the suction side of said pump, said conduit system adapted to receive unburned fuel from said combustion chamber and to return the same to said suction pump, a valve in said conduit system for governing the flow of fuel collected from said combustion chamber to said pump, and means responsive to the oil passing into said system for controlling the operation of said valve, said means acting to

automatically open said valve to permit a predetermined quantity of the collected oil to flow to said suction pump and to be closed when an abnormal quantity of oil passes into said conduit system.

12. In an oil burner the combination of a combustion chamber, a fuel supply therefor, a suction pump for controlling the movement of fuel from said supply to said combustion chamber, a closed fuel conduit system connecting said combustion chamber to the suction side of said pump, said conduit system adapted to receive unburned fuel from said combustion chamber and to return the same to said suction pump, a valve in said conduit system for governing the flow of fuel collected from said combustion chamber to said pump, means responsive to the oil collected for controlling the operation of said valve, said means acting to automatically open said valve to permit a predetermined quantity of the collected oil to flow to said suction pump and to be closed when an abnormal quantity of oil passes into said conduit system, and a switch associated with said valve controlling means for stopping the operation of said pump when an abnormal quantity of unburned fuel has been collected.

13. In an oil burner the combination of a combustion chamber, a fuel supply therefor, fuel ignition means, a safety device responsive to fuel collected from said combustion chamber, said safety device comprising a closed conduit system connecting said combustion chamber and said fuel supply, a reservoir in said conduit system for receiving unburned oil from said combustion chamber, a valve in said reservoir for controlling the flow of the collected fuel to said supply, and a float in said reservoir adapted to be moved by the quantity of oil collected therein, said float acting to automatically open said valve when a relatively small quantity of oil is received in said reservoir and acting to close said valve when an abnormal quantity of oil has been received therein.

14. In an oil burner the combination of a combustion chamber, a fuel supply therefor, fuel ignition means, a safety device responsive to fuel collected from said combustion chamber, said safety device comprising a closed conduit system connecting said combustion chamber and said fuel supply, a reservoir in said conduit system for receiving oil from said chamber, a valve in said reservoir for controlling the flow of the collected fuel to said supply, a float in said reservoir adapted to be moved by the quantity of oil collected therein, said float acting to automatically open said valve when a relatively small quantity of oil is received in said reservoir and acting to close said valve when an abnormal quantity of oil has been received therein, and means operated by said float when influenced by the abnormal quantity of

oil to stop the flow of fuel to said combustion chamber.

15. In an oil burner the combination of a combustion chamber, a fuel supply therefor, fuel ignition means, means for operating the burner, a closed fuel conduit system connecting said combustion chamber and said fuel supply for receiving unburned fuel from said chamber, a reservoir in said conduit system, means for automatically permitting the flow of a predetermined quantity of fuel from said chamber to said fuel supply, said means acting to stop that flow when an abnormal quantity of fuel is received from said combustion chamber, a switch associated with the means for operating said burner and with the means in said reservoir and acting to stop said burner when the abnormal quantity of fuel has been received in said reservoir, and a manually operated valve in said conduit system for draining a predetermined amount of oil from said reservoir after said burner has been stopped due to the presence of abnormal quantity of collected oil.

16. In an oil burner the combination of a combustion chamber, a fuel supply therefor, fuel ignition means, means for operating the burner, a closed fuel conduit system connecting said combustion chamber and said fuel supply for receiving unburned fuel from said chamber, a reservoir in said conduit system, means for automatically permitting the flow of a predetermined quantity of fuel from said chamber to said fuel supply, said means acting to stop that flow when an abnormal quantity of fuel is received from said combustion chamber, a switch associated with the means for operating said burner and with the means in said reservoir and acting to stop said burner when the abnormal quantity of fuel has been received in said reservoir, a manually operated valve in said conduit system for draining a predetermined amount of oil from said reservoir after said burner has been stopped, and means for returning this drained oil to said fuel supply without exposing the same to atmosphere.

17. In an oil burner the combination of a combustion chamber, a fuel supply therefor, fuel ignition means, means for operating the burner, a closed conduit system connecting said combustion chamber and said fuel supply, a reservoir in said conduit system, a valve in said reservoir for controlling the flow of fuel collected from said combustion chamber to said fuel supply, a float in said reservoir responsive to the quantity of oil therein to control the opening and closing of said valve, a switch connected to the means for operating the burner and being operated by said float when the same is raised when an abnormal quantity of fuel is received from said combustion chamber to stop the flow of fuel to said combustion chamber, a second valve mounted in said conduit system for draining

- a predetermined quantity of the oil from said reservoir, and a second reservoir for receiving the drained oil, said second reservoir being connected to said fuel supply.
- 5 18. In an oil burner the combination of a combustion chamber, a fuel supply therefor, fuel ignition means, fuel collecting means associated with said combustion chamber for receiving unburned oil within said chamber,
- 10 a reservoir connected with said collecting means for receiving the oil collected, a closed conduit leading from said reservoir to said fuel supply, a valve in said reservoir for regulating the flow of fuel from said reservoir to
- 15 said fuel supply, a safety switching means for stopping the flow of fuel to said combustion chamber under abnormal conditions, and means mounted within said reservoir and responsive to the oil fuel collected therein, said
- 20 collected fuel responsive means being associated with said switching means to operate the same when an abnormal quantity of fuel is collected in said reservoir.
19. In an oil burner, the combination of a
- 25 combustion chamber, a fuel supply therefor, a suction pump for moving oil from said supply to said combustion chamber, a pipe connected to said combustion chamber for receiving the unburned oil therein, a reservoir
- 30 mounted on said burner and adapted to receive the oil from said pipe, a closed conduit connecting said reservoir to the suction side of said pump, a valve in said reservoir for connecting the same to said closed conduit, a float mounted in said reservoir and adapted to operate said valve and to be responsive to the level of collected oil therein, said valve being automatically opened by said float due to the collection of a normal amount of oil obtained when combustion is initiated in said
- 35 combustion chamber, said float adapted to be moved to close said valve when an abnormal amount of oil has been collected due to non-initiation of combustion in said combustion chamber, a stem moved by said float, a switch for controlling the operation of said suction pump, said switch being connected to said stem and opened thereby when an abnormal quantity of oil is received in said reservoir to thereby stop the operation of said pump,
- 40 a manually operated valve for partially draining said reservoir after having been substantially filled by an abnormal quantity of collected oil, a second reservoir connecting said valve to said closed conduit to permit
- 45 the suction to withdraw the oil in said second reservoir when said pump is again started.
- This specification signed this 28th day of January, 1926.
